Arthur B. Spaulding,
Attorney

UNITED STATES PATENT OFFICE.

WILLIAM HENRY LEGATE, OF WEST HARTFORD, CONNECTICUT, ASSIGNOR OF ONE-HALF TO EDWIN E. SAGE, OF HARTFORD, CONNECTICUT.

PROCESS OF COATING METALS.

Application filed April 23, 1926. Serial No. 104,219.

My invention relates to processes for applying finishing surfaces of metal of various kinds to articles, and an object of my invention, among others, is the production of a process by means of which a coating material of increased thickness may be applied to portions of articles in a particularly rapid and efficient manner.

One way of practicing my improved process and in the carrying into effect of which the objects herein set out, as well as others, may be attained, is illustrated in the accompanying drawings, in which—

Figure 1 is a face view of a spoon blank in its flat form and having a shield applied thereto as one of the steps in the practice of my improved process.

Figure 2 is a view in section through the same illustrating the manner of applying a flux, as well as a deposit of metal.

Figure 3 is a view of the spoon after having been shaped and prior to the deposit of the covering coating of metal thereon.

Figure 4 is a view of the finished spoon.

While my invention is particularly adapted to the process of applying a finished surface to flatware, such as spoons, forks and the like, it will be understood that it may be equally well applied to the formation of other articles or devices where a deposit of metal, as in the form of letters or ornamentation, is desired, and, therefore, while I have selected a spoon as an article in connection with which my invention is disclosed herein, it will be understood that the invention is not limited to such.

In finishing articles of tableware, such as spoons, forks and the like, an extra thickness or deposit of precious metal is applied to those portions of the article subject to the greatest wear, as to the outside of the bottom of the bowl, and the curved part near the tip of the handle. This has been applied in various ways that has required more or less labor, and expense.

By the practice of my improved process I am enabled to obtain this extra thickness of metal in an extremely simple and inexpensive manner.

In practicing my improved process an article, as a spoon or fork, commonly composed of German silver, is taken in its flat state, and is properly treated to place its surface in required condition for the subsequent operations. I then place a shield, as

6, upon this blank 5, this being substantially of the shape of the article being operated upon, but of a size to thoroughly cover it. This shield has an opening 7 located at that part corresponding to the bottom of the bowl, an opening 8 at that part corresponding to the curve near the tip of the handle. The shield is cut off at that part corresponding with the point of the bowl of the spoon so that when the shield is placed in position 60 the parts mentioned are uncovered.

A flux of any competent kind is now introduced through said openings and at the vacant spot 9 at the tip. In a preferred manner of applying this flux I use a nozzle, 70 as 10, by means of which the flux is sprayed through the openings. This flux will be such as to cause a metal subsequently applied to adhere tenaciously to the article being treated.

After the flux has been applied a layer of metal, as sterling silver, is introduced through the openings in the shield, and this may be applied as by spraying the molten silver through the openings, or in any other 80 desired manner, upon the flux previously applied, the thickness of the coating of silver or other metal thus applied depending in a measure upon the thickness of the shield, that is, the thickness of the metal will not be greater than that of the shield. It will be understood that the shield is preferably constructed of some material, as asbestos, that will not be injuriously affected by the heat.

After the coating of silver or other metal 85 has been applied and affixed to the blank, as denoted by the numerals 11, 12 and 13, said blank is formed into final shape, as by means of the action of a drop press, or other device thereby producing the article 14, as shown 90 in Figure 3. This article is now suitably finished, as by polishing, buffing, &c., and then it is ready for plating in the ordinary manner, and after such plating has been applied there will be an extra thickness of 100 the precious metal at the outer surface of the bottom of the bowl, at the tip of the bowl, and at the point near the tip of the handle, the article shown in Figure 4 being the final result of the various operations.

While I have described herein the operation of supplying the different materials to the blank at certain stages with respect to the formation of the latter, it will be understood that the invention is not limited to 105 110

the application of the plating materials at any designated stage in the formation of the blank.

While many well known kinds of flux will 5 serve the purpose of causing the silver to adhere to the blank, among several I have found to satisfactorily answer the purpose is one composed of salammōniac and sulphate of zinc in the proportions of twenty 10 ounces of the former to eight pwts. of the latter.

In accordance with the provisions of the patent statutes I have described the principles of operation of my invention, together 15 with the process and device which I now consider to represent the best embodiment thereof, but I desire to have it understood that the device shown is only illustrative and that the process may be carried out by other 20 means and applied to uses other than those above set out.

I claim—

1. In the art of plating, the process for increasing the thickness of a piece of material while in its embryo state and which material when completed assumes a different configuration, said process consisting in applying to the piece of material to be thickened, a shield of a design similar to the embryo material to completely overlie the material with the exception of cut-out and cut away portions of the shield, then spraying a material having an affinity for the thickening material to the exposed portions of the 35 piece of material to be thickened, then ap-

plying thickening material to said exposed parts resulting in amalgamation between the material to be thickened and the thickening material, shaping the piece of material into its completed form, and plating the entire 40 article to produce a plain effect.

2. In the art of plating, the process for increasing the thickness of a metallic article while in its embryo state before completion consisting of applying a shield to the article 45 with portions of the shield removed at points corresponding to the greatest points of wear of the article, spraying a flux on the article through the openings in the shield, then applying the thickening material through said 50 openings resulting in amalgamation between the material to be thickened and the thickening material and finally plating the article whereby the outer faces of the thickened portions and coating are substantially 55 continuous.

3. In the art of plating, the process for increasing the thickness of a metallic article at restricted areas and wherein said restricted areas comprise smooth and plain surfaces, 60 said process consisting of first applying a flux to the smooth restricted areas, then applying molten metal to the restricted areas resulting in amalgamation between the molten metal and the metallic article and 65 finally plating the entire article whereby the initially thickened portions are substantially continuous with the remaining surface of the article.

WILLIAM HENRY LEGATE.
